[57] CLAIM

The ornamental design for a motorcycle tail light, substantially as shown and described.

DESCRIPTION

FIG. 1 is a top plan view showing our new design for a motorcycle tail light;

FIG. 2 is a side elevational view thereof, the opposite side being a mirror image;

FIG. 3 is a bottom plan view thereof;

FIG. 4 is an end elevational view thereof, the opposite end being a mirror image;

FIG. 5 is an end elevational view showing a second embodiment thereof;

FIG. 6 is a top plan view of the second embodiment;

FIG. 7 is a side elevational view of the second embodiment, the opposite side being a mirror image.

The bottom of the second embodiment is identical to the bottom of the first embodiment. The base of the tail light is reflective, the stippled strip is translucent and the cover is transparent.
